UNITED STATES PATENT OFFICE

90,602

DESIGN FOR A CAMERA CASING

Walter D. Teague, New York, N. Y., assignor to
Eastman Kodak Company, Rochester, N. Y.,
a corporation of New York

Application June 24, 1933. Serial No. 48,527

Term of patent 7 years

To all whom it may concern:

Be it known that I, WALTER D. TEAGUE, a citizen of the United States of America, residing at New York city, in the county of New York and State of New York, have invented a new, original, and ornamental Design for Camera Casings, of which the following is a specification, reference being had to the accompanying drawing forming a part thereof in which

Figure 1 is a front elevation of a camera constructed in accordance with and showing my new design. Figure 2 is a top plan view of the camera shown in Figure 1. Figure 3 is a rear elevation of the camera shown in Figure 1.

The cross lines in the drawing are not intended to represent any one color but to indicate that all of that portion of the drawing which is cross-lined is of a single shade or color and the cross lines are intended to illustrate different shades or intensities of the decorative panels as distinguished from the parts of the camera which are not cross-lined.

I claim:

The ornamental design for a camera casing as shown and described.

Signed at Rochester, New York, this 20 day of June, 1933.

WALTER D. TEAGUE.
